UNITED STATES PATENT OFFICE.

WILLIAM H. HEFFLEY, OF DUNCANNON, PENNSYLVANIA.

GAME DEVICE.

1,209,963.

Specification of Letters Patent. Patented Dec. 26, 1916.

Application filed January 27, 1916. Serial No. 74,661.

To all whom it may concern:

Be it known that I, WILLIAM H. HEFFLEY, a citizen of the United States, residing at Duncannon, in the county of Perry and State of Pennsylvania, have invented certain new and useful Improvements in Game Devices, of which the following is a specification, reference being had to the accompanying drawings.

10 This invention relates to game devices and has for its primary object to provide a game attachment for pool tables whereby a variety of novel and amusing games may be played.

15 It is another and more particular object of the invention to provide means arranged in juxtaposition to the pockets of a pool table and actuated by the impact of the ball to operate the pointer of a counter, the number indicated by the counter when it comes 20 to a position of rest being credited to the score of the player, according to the rules of the game.

25 It is an additional object of my invention to provide a device for the above purpose, embodying a casing suitably fixed in the marginal wall of the table, centrally of the pocket wall, and having its upper surface suitably numbered or provided with other 30 value indicating characters, a spinning pointer adapted to operate over the numbered surface, and means mounted within the casing for actuating said pointer including an impact receiving element movable 35 through one wall of the casing and extending into the pocket.

With the above and other objects in view, my invention consists in the novel features of construction, combination and arrangement of parts to be hereinafter more fully described, claimed and illustrated in the accompanying drawing, in which,

40 Figure 1 is a fragmentary top plan view of a pool table showing my improved game device applied thereto; Fig. 2 is an enlarged vertical section; Fig. 3 is a horizontal section taken on the line 3—3 of Fig. 2; Fig. 4 is a horizontal section similar to Fig. 3, illustrating a slightly modified form of the device; and Fig. 5 is a horizontal section showing still another alternative construction.

45 Referring in detail to the drawing and more particularly to Figs. 1, 2 and 3 thereof, Fig. 5 designates generally a pool table having 55 the usual marginal rails 6. The table 5 is provided at its corners and at the center of

the longitudinal rails with the usual ball receiving pockets 7. The wall of each pocket 7, centrally thereof, is mortised or recessed, as indicated at 8, to receive a casing 9 which 60 is fixed to the rails of the table by means of suitable screws indicated at 10. The upper surface of this casing is flush with the rail surfaces and, upon the same, the numerals 11 are stamped or otherwise delineated. In 65 the top and bottom walls of the casing 9, a shaft 12 is rotatably mounted, and upon the upper end of this shaft the pointer 13 is loosely mounted. Immediately beneath the pointer, a ratchet disk 14 is fixed upon the 70 shaft 12 and said pointer carries a spring-pressed pawl 15 for engagement with the teeth of this ratchet so that the pointer will be locked to the shaft for rotation therewith in one direction.

75 A star wheel 16 is fixed upon the shaft 12 within the casing 9 and is engaged by the lug 16' on the bar 17 mounted to reciprocate through said casing. One end of this bar is offset, as at 18, and extends exteriorly of 80 the casing and radially with respect to the pockets 7. To this offset end 18 of the bar, a curved arm 19, substantially concentric with the wall of the pocket 7, is fixed, and is suitably padded so that the surfaces of the 85 balls will not be marked by contact therewith. The bar 17 within the casing 9 is formed with a laterally projecting lug 20 to which one end of a spring 21 is secured, the other end of said spring being fixed to 90 the wall of the casing 9.

95 It will be readily understood that, in the operation of the device as above described, the ball, when pocketed by the player, will strike the padded arm 19 and force the bar 17 inwardly. The lug 16' engaging the wheel 16 rotates the shaft 12, and the pawl 15 being engaged by the ratchet 14, the pointer 13 is rotated with said shaft. The 100 spring 21 is, of course, stretched and placed under tension so that when the impact force upon the bar has been expended, said spring will contract and reverse the movement of said bar, thus also reversing the rotation of the shaft 12. The pointer 13, however, will 105 continue to turn or rotate as the pawl 15 thereon will move idly over the reversely rotating ratchet 14. The rotation of the pointer gradually slows down until it finally 110 comes to a stop over one of the numerals 11 on the upper face of the casing 9. The number indicated thereby is placed to the

credit or discredit of the player as the case may be, in accordance with the rules of the particular game.

It is manifest that a great variety of games might be played by means of the device, in connection with the ordinary game of pool. It is further apparent that various other mechanisms might be employed for causing a rotation of the indicating pointer or arrow when the ball is pocketed, certain of which I have shown in Figs. 4 and 5 of the drawings, and which may be explained as follows:

In Fig. 4, I have shown an ordinary spiral clock spring 22 arranged within the casing 9 and fixed at one of its ends to the shaft or spindle 12 and at its other end to the wall of the casing 9. In this case, the pointer or arrow is fixed to the upper end of the vertical shaft. Upon said shaft within the casing, a ratchet disk 23 is also secured, with which the end of a pivoted pawl 24 is normally held in engagement by means of the spring 25 bearing against the free end of said pawl. A bar 17, similar to the bar 17' above described, is movable through the side wall of the casing and has its inner end disposed between the ratchet disk 13 and the pawl 24 and in juxtaposition to the latter. The other end of said bar is equipped with a curved padded arm for engagement by the ball as above referred to. A suitable knurled head or button is fixed to the upper end of the shaft 12 so that said shaft may be conveniently rotated and the spiral spring 22 wound about said shaft. Immediately upon the ball striking the arm 19 the rod or bar 17' acts to release the pawl 24 from engagement with the ratchet 23 so that the spring will unwind and thus rotate the shaft and spin the pointer. The spring 22 is of such tensile strength that it will unwind only partially unless the impact of the ball against the arm 19 is sufficiently forcible to force the bar 17' to the limit of its inward movement and thus hold the pawl 24 out of engagement with the ratchet 23 for a sufficient length of time to permit of the full unwinding of the spring. Thus, it will be seen that the extent of rotation of the indicating pointer will vary in accordance with the pressure of the ball upon the impact receiving arm.

In Fig. 5 of the drawing, I have shown a series of blades or vanes 26 fixed to the shaft 12 and extending radially therefrom. The inner side of the casing 9 is open and, to the same, the wall of an air bulb 27 is suitably secured. This bulb is preferably of rubber or other elastic material and the wall which is opposed to the interior of the casing 9 is formed with a directing discharge nipple 28 which operates to direct the air against the vanes or blades 26 and thus rotate the shaft 12 and the pointer fixed to the upper end there-

of. It will be understood that the air bulb 27 is of such proportions that it will not interfere with the gravity movement of the ball into the pocket.

From the above description, taken in connection with the accompanying drawing, it is believed that the construction, manner of use and several advantages of the device will be clearly and fully understood.

I have herein disclosed several alternative forms of the invention, but it is apparent that numerous other mechanisms might be devised for the operation of the indicating pointer. It is therefore, to be borne in mind that I do not consider myself restricted to any of the several illustrated mechanisms referred to in the practical adaptation and application of the invention. Such a device affords means for playing various amusing games wherein the ordinary pool balls are utilized. The device can be readily applied to pool tables of the usual construction without requiring any material alterations therein. In view of the simplicity of the invention, it will further be appreciated that the same is very durable and not liable to get out of order.

While I have shown and described the preferred construction and arrangement of the several parts, it is, nevertheless, to be understood that the device is susceptible of various modifications therein without departing from the essential features or sacrificing any of the advantages of the invention as claimed.

Having thus fully described my invention, what I desire to claim and secure by Letters Patent is:—

1. The combination with a table having a ball receiving pocket, of a rotary indicator mounted upon the table adjacent to said pocket, and operating means for said indicator having an impact receiving member projecting into the pocket.

2. The combination with a table having a ball receiving pocket, of a rotary indicator mounted upon the table adjacent to the outer side of the pocket, and means for operating the indicator including an impact receiving member adapted to be engaged by the ball when driven into the pocket.

3. The combination with a table having a pocket, of a game device including a dial and a rotatable pointer movable thereover, and means for operating said pointer including an actuator extending radially into the pocket for engagement by a ball.

4. The combination with a table having a pocket, of a game device including a dial permanently mounted in the surface of the table contiguous to said pocket, a rotatable pointer movable over the dial, and means for operating said pointer including a spring held actuator projecting radially into the pocket for engagement by a ball.

5. The combination with a table having a pocket, of a casing permanently mounted in the table and having a dial face flush with the surface of the table, a shaft rotatably mounted in the casing, a pointer on said shaft movable over the dial, and means for rotating said shaft including a rectilinearly movable actuating element projecting into the pocket for engagement by a ball.
- 10 6. The combination with a table having a pocket, of a game device including a casing fixed in the table and having a dial face flush with the surface thereof, a shaft rotatably mounted in the casing, a pointer on
- 15 said head movable over the dial face, and means for rotating said shaft including a spring held actuating element movable through one wall of the casing and projecting radially into the pocket, and a curved padded arm fixed to said element for engagement by a ball.
- 20 In testimony whereof I hereunto affix my signature in the presence of two witnesses.

WILLIAM H. HEFFLEY.
